BUILDING STRUCTURE

Shepard Vogelgesang, R.D. 2, Dalton, Whitefield, N.H.
Filed Apr. 4, 1962, Ser. No. 184,976
8 Claims. (Cl. 52—82)

This invention relates in general to building constructions and more particularly to a new and improved building structure.

It is an object of the present invention to provide a new and improved building structure.

It is another object to provide a building structure which is simple in construction and incorporates a new and improved framework.

It is still another object to provide a building structure which can readily be assembled initially as a simple single floor dwelling, for example, and subsequently expanded with a minimum of effort to an elaborate multiple floor structure.

It is yet another object to provide a new and improved building structure having predominantly external structural supports so as to permit substantial freedom of internal planning on each floor of the structure.

It is yet a further object to provide a building structure of the aforescribed character which is simple and inexpensive to construct yet which is structurally more rigid than generally similar constructions heretofore utilized.

It is still a further object to provide a building structure incorporating a framework construction which defines a base readily adaptable to irregular terrain.

It is another object to provide a building structure wherein rainwater and snow, for example, are projected far from the structural supports and doors and windows of the structure to provide maximum shelter from the elements.

It is still another object to provide a building structure of the immediately aforescribed character which shades the sides of the building and doors and windows to assure deep shadows during the northern hot months of the year and excellent sun penetration during the northern cold months of the year.

It is yet a further object to provide a building structure incorporating a framework construction which can be simply pre-engineered and pre-fabricated for assembly in the field.

The above and other objects are realized in accordance with the present invention by providing a new and improved building structure. The invention contemplates the use of a framework comprising at least two frame members, each having a configuration generally resembling a C. Each C-frame member includes two substantially right angle component members having adjacent ends tied together at the apex of the roof of the building structure and their opposite ends mounted in foundation supports or otherwise tied together at the base of the structure. Each C-frame is, in turn, interconnected with each other C-frame at the apex of the roof of the building structure.

The right angle component members are each inclined at a predetermined angle to the horizontal to form an upwardly diverging side frame work for the building structure and an upwardly converging roof framework. A floor seats within the cooperating C-frames and rests on the diverging side framework developed thereby so as to urge the frame component members outwardly against the ties at the apex and at the base of the building structure and form a solidly rigid building framework.

Conventional roofing is readily supported by the roof framework while conventional siding might be supported in vertically extending relationship on the floor or in upwardly diverging relationship in keeping with the con-

2

figuration of the side framework. The floor forms a roof for a lower level in the building structure if such a lower level is desired. In the event such a lower level is desirable, conventional siding is easily constructed from the ground support below it.

The invention, both as to its organization and method of operation, taken with further objects and advantages thereof, will best be understood by reference to the following description taken in connection with the accompanying drawings, in which:

FIGURE 1 is a perspective view of a building structure embodying the features of the present invention;

FIGURE 2 is a front elevational view of the building structure illustrated in FIGURE 1;

FIGURE 3 is a front elevational view of a C-frame which forms a component of the framework in the building structure shown in FIGURES 1 and 2;

FIGURE 4 is a plan view of the framework and floor embodied in the building structure illustrated in FIGURES 1 and 2, showing additional bracing framework incorporated;

FIGURE 5 is an enlarged fragmentary view of the apex of the framework illustrated in FIGURE 4; and

FIGURE 6 is a sectional view taken through a building structure similar to that illustrated in FIGURE 2 with a lower dwelling level added.

Referring now to the drawings and particularly to FIGURES 1 and 2, a building structure embodying the features of the present invention is illustrated generally at 10. The building structure 10 includes a framework 11 which supports a hipped roof 12 and a floor 13, as well as siding 14, from the terrain 15. The framework 11 includes a pair of C-frames 20 and 21 which are tied together at the apex of the roof of the building structure 10 and are mounted in foundation supports or otherwise tied together at the base of the structure; in other words, at the level of the terrain. The roof 12 is inclined inwardly while the siding 14 is supported on the floor 13 within the confines of the C-frames 20 and 21 in upwardly diverging relationship.

The floor 13 urges the C-frames 20 and 21 outwardly at a point between the lower ends of the C-frames, which are supported in a foundation, for example, and the apex of each C-frame, which is continuous. In other words, the floor 13 reacts against ties effectively provided at the apex and the base of the framework 11. This insures a solidly rigid framework 11 for the structure 10.

As seen in FIGURE 3, the C-frame 20 comprises oppositely disposed right angle frame members 30 and 31. The right angle frame members 30 and 31 each include a lower leg 35 and an upper leg 36 rigidly secured together at an angle of 90°, by any conventional means, as at 37. In practice, this angle might be rigidly maintained by the provision of vertical braces such as are illustrated at 38 in FIGURE 3, or in the alternative by gussets such as illustrated at 39. In effect, the right angle frame members are unitary in construction. Each right angle frame member 31 is secured at the apex of the building structure 10 to its oppositely disposed counterpart frame member 30 through a connector ring assembly 40. As will be seen, the legs 35 of the opposed frame members 30 and 31 diverge upwardly to the legs 36 from an imaginary common point beneath the terrain. The legs 36 in turn, converge upwardly to an apex at the connector ring assembly 40. Each pair of oppositely disposed legs 36 forms a back member defining ridges in the hipped roof 12.

The base 41 of each leg 35 might be seated in a foundation support of concrete, for example, or in the case of sandy or loamy soil, the oppositely disposed legs 35 might be otherwise tied together at their lower ends. The C-frame 21 is identical in construction to the C-frame 20,

and consequently is not described in detail here. Identical components of each of the C-frames are identified by identical reference numerals.

As further seen in FIGURE 3, the floor 13 of the building structure 10 rests on the upwardly diverging legs 35 of each C-frame. Consequently, the right angle frame members 30 and 31 are wedged outwardly against the ties established by the connector assembly 40 at the apex of the building structure and by the foundation, for example, at the base of the building structure. As a result, the C-frames 20 and 21 are maintained in rigid relationship by the floor 13 and the framework 11 is also rigidified. The legs 35 preferably extend at an angle of 60° or thereabouts to the horizontal, although this might be varied within limits.

Referring now to FIGURE 4, it will be seen that, in plan, the C-frames 20 and 21 are preferably interconnected at the connector assembly 40 in substantially right angle relationship. It is conceivable, of course, that more than two C-frames might be utilized, in which case the C-frames would be spaced at lesser angles. The floor 13 seated within the C-frames includes and is supported by generally horizontal beams 42 which extend around the periphery of the floor 13 and are joined to corresponding legs 35 of the framework 11 in any well known manner.

To rigidify the entire framework 11 against parallelogram type deformation in the plane of the floor 13, triangular bits 43 are sometimes extended from the midpoint of the beams 42 (see in dotted lines in FIGURE 4) and the floor joists 44 laid diagonally of the beams 42, extending into the triangular bits 43. The floor 13 would then be star shaped, of course, and the roof 12 would be similarly designed in plan.

The connector assembly 40 preferably comprises a plurality of generally irregularly shaped tie straps 45 composed of steel strip, for example. As will be seen, each strap 45 includes a pair of oppositely disposed arms 46 extending at substantially right angles to each other and connected through an appropriate leg 36 of a corresponding C-frame to an oppositely disposed corresponding leg 46 of the opposed strap member 45, preferably by conventional machine bolts 47. It will be noticed, of course, that when the right angle frame members 30 and 31 of each C-frame are secured together by the connector assembly 40, a substantially circular aperture remains through the connector assembly 40. This aperture is optional and finds utility as a passage for a chimney 50 from a stove (not shown) which might be supported within the structure 10. In this respect, the weight of the chimney is additionally effective to further stiffen the framework 11.

Referring to FIGURES 1 and 4, it will be seen that after C-frames 20 and 21 are set up in the manner hereinbefore described, cross joists 51 and roof joists 52 are preferably placed on and firmly secured to (by conventional means) the upwardly converging legs 36 of the C-frames to form a part of the roof 12. Subsequently, conventional roofing material of any well known composition might be secured to the roof joists 52.

In turn, the siding 14 is preferably fabricated in any well known manner and supported on the floor 13 of the structure 10. The siding 14 might include picture windows 53 and be inclined outwardly and supported by corresponding portions of the upwardly diverging legs 35 of the C-frames 20 and 21. On the other hand, the siding 14 might extend upwardly in perpendicular relationship from the floor 13 and join the roof 12 somewhat further inwardly of its outermost extremities. In either case, however, it should be remembered that the details of construction of the siding 14 are conventional, and the siding might include prefabricated panels or the like.

It will be seen that a building structure has been provided which affords a simply constructed, yet solidly rigid dwelling or the like. It can be made in a single level embodiment as shown in FIGURES 1 and 2, in which case

an entrance way (not shown) is preferably provided extending upwardly through the floor 13 or from the terrain at one side of the structure 10. In this light, the legs 35 of the C-frames 20 and 21 can readily be individually shortened to any extent so as to adapt the structure for seating on terrain of virtually any contour. As will be also seen, support posts 54 might be set under the floor 13 adjacent the corners of the floor so as to extend downwardly into adjacent relationship with the upwardly diverging legs 35 of corresponding frames. These support posts 54 provide bracing for the floor 13 inwardly of the connection between the floor 13 and the upwardly diverging legs. This inner support reduces the bending stress built up in the floor by the weight of the floor itself and the weight of the contents of the structure 10 resting on the floor.

A highly advantageous feature of the present invention is the ability of the structure to be readily modified for inclusion of another level. Referring now to FIGURE 6, it will be seen that the legs 35 of the framework 11 can be extended a sufficient distance below the floor 13 to facilitate the building of a ground level, seen generally at 60, under the floor 13. In such case, of course, the chimney 50 might extend downwardly through the floor 13 so that a centrally disposed fireplace 61 could be built in the center of the floor 62 of the lower level 60.

The lower level 60 is then provided with siding 63 in any well known manner to complete the building structure 10 as a two-level construction. Access to the lower level 60 might then be attained from the level of the terrain, of course, and access to the upper level through a stairway (not shown) through the floor 13 of the upper level, for example.

As will be seen, the building structure 10 can readily be expanded with a minimum of effort from a single level structure to a somewhat more elaborate multiple level structure. At the same time, due to the fact that the support provided the structure 10 by the framework 11 is entirely external of the dwelling itself, complete freedom of internal planning is afforded on each level of the building structure.

Whether the building structure 10 is developed as a single or as a multiple level structure, it will be seen that the roof 12 projects rain and melting snow far outwardly from the sides of the building. Consequently, maximum shelter from water and ice is assured. This is important, since building structures of the type embodying the features of the present invention find utility as resort cabins for skiing, or the like. In contrast, however, they might also be utilized in tropical environs or the like.

The upwardly diverging wall construction provided by the C-frame basic framework 11 affords shade on the sides of the building and at the doors and windows during the northern hot months of the year. On the other hand, the sun penetration during the northern cold months of the year is excellent.

The C-frames 20 and 21 are readily pre-engineered and pre-fabricated, of course. It is only necessary that the rigid right angle frame members 30 and 31, each of which might be a heavy laminated, interlocking beam construction, be fabricated at a factory, for example. Once delivered to a building site the lower ends of the beams forming the legs 35 of the framework 11 can readily be sheared off, as at 41, to conform to the terrain while the upper legs 36 are secured together by a connector assembly 40. The beams 42 forming the base of and supporting the floor 13 can then readily be set in place and secured to the upwardly extending legs 35. The siding 14 and the roof 12 can be prefabricated for easy installation, if desired, as has been pointed out.

The result is a building structure which is strong and rigid, extremely simple in construction, and which affords consummate ease of modification. In addition, as has been pointed out, the structure is readily adaptable to any terrain as well as being greatly protective of the sides and

base of the building structure and the occupants from the elements. Furthermore, the four point support concept minimizes the danger of attack by chewing insects or rodents, for example.

Although the C frame building would normally be constructed with wood framing, other materials might be used as well. The use of steel, for example, permits the construction of much larger structures.

While an embodiment described herein is at present considered to be preferred, it is understood that various modifications and improvements may be made therein, and it is intended to cover in the appended claims all such modifications and improvements as fall within the true spirit and scope of the invention.

What is desired to be claimed and secured by Letters Patent of the United States is:

1. A building structure for support on terrain comprising: a framework, said framework comprising a plurality of generally C-shaped frame members, each frame member including a back member and a pair of legs depending therefrom, each pair of depending legs having lower free ends and diverging upwardly from an imaginary point below their free lower ends, means firmly mounting said free ends on the terrain so they cannot be forced away from each other, each back member including a pair of upwardly converging legs, each upwardly diverging leg being rigidly connected to a corresponding upwardly converging leg at substantially at right angle, floor means wholly supported by said upwardly diverging legs within said framework so that the bulk of its weight tends to urge said depending legs outwardly against the constraining influence of said mounting means and said back member.

2. The building structure of claim 1 further characterized in that each of said upwardly diverging legs is inclined at an angle of in the neighborhood of about 60° to the horizontal.

3. A building structure comprising: a framework supporting a hipped roof defining an apex of the structure, said framework comprising a plurality of generally C-shaped frame members each of said frame members including a pair of substantially unitary angle members interconnected at the apex of the building structure, each interconnected pair of angle members extending downwardly from said apex into engagement with foundation means, each pair of angle members including lower portions thereof diverging upwardly from an imaginary point below said foundation means and upper portions thereof converging upwardly to said apex, floor means wholly supported by said upwardly diverging legs within said framework so that the bulk of its weight tends to urge said angle members outwardly against the constraining influence of their interconnection and said foundation means.

4. A building structure comprising: a framework, said framework comprising a plurality of generally C-shaped frame members, each of said frame members including a pair of unitary angle members interconnected at an upper

apex by tie means, each interconnected pair of angle members extending downwardly from said apex into engagement with foundation means, each pair of angle members including lower portions thereof diverging upwardly from an imaginary point below said foundation means and upper portions thereof converging upwardly to said apex, floor means wholly supported on said upwardly diverging lower portions within said framework so that the bulk of its weight tends to urge said angle members outwardly against the constraining influence of said tie means and said foundation means.

5. The building structure of claim 4 further characterized in that each pair of angle members is interconnected with each other pair of angle members by said tie means.

6. A building structure comprising: a framework, said framework comprising a plurality of generally C-shaped frame members, each of said frame members including a pair of unitary right angle members interconnected at an upper apex of the building structure, each interconnected pair of right angle members extending downwardly from said apex into engagement with foundation means, each pair of right angle members including lower portions thereof diverging upwardly from an imaginary point below said foundation means and upper portions thereof converging upwardly to said apex, floor means wholly supported by said upwardly diverging legs within said framework so that the bulk of its weight tends to urge said right angle members outwardly against the constraining influence of the interconnection between said angle members and said foundation means.

7. The building structure of claim 6 further characterized by and including hipped roof means supported by said upper portions, said upper portions defining the ridges in said hipped roof.

8. The building structure of claim 6 further characterized in that said framework comprises two generally C-shaped frame members extending substantially perpendicular to each other, said floor means including beams extending between and secured to adjacent lower portions of said right angle members, and floor joist means running diagonally of and supported by said beams to prevent deformation of said floor in the plane thereof.
